(57) **CLAIM**

We claim the ornamental design for an operational panel for digital multifunction printer, as shown and described.

DESCRIPTION

FIG. 1 is a front view of an operation panel for digital multifunction printer showing our new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a cross-sectional view of the operation panel for digital multifunction printer along lines 7-7 shown in FIG. 1; and,

FIG. 8 is another cross-sectional view of the operation panel for the digital multifunction printer along lines 8-8 in FIG. 1.

1 Claim, 8 Drawing Sheets
